UNITED STATES PATENT OFFICE.

ALBERT GODSHO, OF PHILADELPHIA, PENNSYLVANIA.

SHOE STRETCHER.

Application filed December 17, 1927. Serial No. 240,895.

My invention relates to shoe stretchers, and aims generally to improve such devices.

Among the important objects of my invention is to provide a stretcher or last adaptable for the manufacture of custom made shoes, as for instance for crippled feet, or for the adjustment and repair of shoes, as for example, to correct certain defects in shoes as heretofore produced upon lasts made according to casts, design or measure. In such cases, the last is usually of special shape and form and it is desirable and necessary to stretch the material of the shoe which may be accomplished with the aid of my invention without 15 distorting the last and without interfering with subsequent operations upon the shoe while on the stretcher.

Other objects of the invention will be apparent to those skilled in the art, from the 20 following description and accompanying drawings, wherein I have selected for illustrative purposes one embodiment of the invention, and wherein:

Fig. 1 is a side elevation partly in section 25 illustrating the stretcher applied to a shoe;

Fig. 2 is a similar showing of the clamping means for holding the shoe in a stretched condition after the stretching mechanism has been removed; and

Fig. 3 is a cross section on the line 3—3 in 30 Fig. 1, showing the details of the swivel connections between the screw and the clamping levers.

The invention comprises separable vamp 35 and heel sections in combination with lever means removably connected with the sections for forcing them apart longitudinally to stretch the material of the shoe, and independent clamping means detachably connected with the sections for holding the sections in an extended position, thereby permitting removal of the lever stretching means.

Referring now more particularly to the embodiment of the invention illustrated in the 45 drawings, the vamp section or form 10 and heel section 11 are separable and are first placed in their respective parts in the shoe. The vamp and heel sections 10 and 11 need not be of a special form corresponding to the shapes of the last but may be skeleton forms which may be further built up, as required for stretching or correcting a shoe to overcome any particular defect or faulty condition therein, or to provide a last of special 55 contour corresponding to the abnormalities of a foot for which a special shoe is be-

ing made. For this purpose, a plurality of apertures such as 12 are appropriately placed in the vamp and heel sections 10 and 11, whereby removable pads, bands, shapes, auxiliary or supplemental sections and the like may be secured upon the sections 10 and 11 in order to stretch the shoe material to prevent pressure upon defects, abnormalities, tender spots or the like upon the foot. Such a 60 pad is shown by way of example, at 12', Figs. 1 and 2.

A suitable stretching mechanism is provided for forcing the vamp and heel sections apart longitudinally, thereby to stretch the 70 shoe, and in the present instance such mechanism comprises a pair of levers 13 and 14 pivotally connected together intermediate their ends, the lower ends thereof carrying pivotally connected pin members 15—16 75 adapted to be removably seated in openings in the inner faces of the vamp and heel sections 10—11 respectively. A nut member 17 is pivotally connected to the upper ends of the lever member 13 in any desirable manner, 80 as by a trunnion 20, and a swivel bearing member 19 is similarly mounted upon the upper end of the lever member 14. A screw-threaded bar 21 is threaded into the nut 17, and is provided with a non-threaded end 22 85 rotatably mounted in the swivel member 19, whereby the upper ends of the lever members may be forced apart by turning the bar. A collar 23 pinned to the bar 21 prevents accidental removal of the member 19 from the 90 bar.

The outer free end of the bar 21 is provided with a suitable handle member 24 by means of which the bar may be rotated. Rotation of the bar in one direction causes the nut 95 member 17 and the adjacent end of the lever 13 to be forced away from the swivel member 19 and the adjacent end of the lever 14, thereby forcing apart the pin members 15 and 16, and the vamp and heel sections 10 and 11, to stretch the shoe longitudinally.

After the shoe has been stretched sufficiently for the purpose desired, it may be locked or clamped in such position, by means of a clamp, and the lever stretching mechanism removed so as to permit further machining operations or repair upon the shoe, as for instance, stitching in a sewing or sole-stitching machine.

In the embodiment of the invention illustrated herein, the clamping means comprises a pair of L-shaped clamping bars 25—26, ar-

ranged so that one of the longer legs thereof overlies the other and is adapted to be clamped in position by means of a suitable clamp 27, thus forming an extensible inverted 5 U-shaped clamping member, the downwardly extending legs 28-29 of which are loosely and movably seated in apertures 30-31 in the vamp and heel blocks, the lower ends of said legs bearing against the front face 32 10 of the aperture 30 in said vamp portion, and against the rear face 33 of the aperture 31 in said heel portion, near the bottoms of said faces. The legs are of such length that their depth of insertion into the apertures is less 15 than the depth of the apertures, in order that they may always exert a wedging action against the vamp and heel portions of the last.

Said front and rear faces 32 and 33 are 20 respectively forwardly and rearwardly inclined from bottom to top, as shown in Fig. 2, whereby the downward legs 28-29 of said clamp force said vamp and heel portions further apart as the legs are further inserted 25 into said apertures. By reason of this arrangement, the vamp and heel portions may be inserted in a shoe and forced apart to the same extent as was originally done by the stretching levers shown in Fig. 1, by inserting 30 said clamp legs 28-29 to the full possible depth in the apertures 30-31. It is to be understood that the inclination of the faces 32 and 33 from the vertical is not so great as to permit slippage of the lower ends 35 of legs 28-29.

In operation, such pads, bands or other attachments as may be indicated by the measurements or cast of the foot for which a shoe is to be made, or fitted, are attached to the 40 vamp or heel section, or both, by means of pegs fitted into the appropriate holes. The vamp and heel portions of the stretcher or last are then put into the shoe and the pins on the lower end of the levers are inserted 45 in the holes. The levers are then spread apart by turning the handle until the vamp and heel members are forced apart the correct distance for the length of the shoe. The clamp, with the screw loosened, is put into 50 position with the legs downward as far as possible in the apertures, and the two portions of the clamp are pushed apart until the bottoms of the legs bear firmly against the faces near the bottom, and are then locked in adjustment by tightening the screw.

The levers and their attached pins are now removed and the heel and vamp portions of the stretcher or last are firmly held in position by the clamp alone. The shoe with the 60 last still firmly in place therein can now be removed for further operations, including machine stitching if necessary. Should it be desired to remove the last, this may be accomplished by pulling the clamp upward, thus 65 releasing the separating pressure on the vamp

and heel portions, which may then be separately removed from the shoe. The last may be re-inserted and correctly adjusted by placing the two portions into the shoe and forcing them apart by pushing the clamp down 70 into position.

My invention is advantageous in shaping or stretching the fabric of shoes and the like to correct them to conform to any desired cast or shape of foot. It is not my intention, primarily, to provide a last over which the shoe is made, but I do provide a stretching device whereby a shoe may be shaped or corrected without changing the general shape of the last. Obviously there are many 80 uses to which my invention is adaptable as will be apparent to the skilled mechanic in the art.

Furthermore, after the material has been stretched, certain parts of the stretching 85 mechanism may be readily removed, and remaining parts held in their stretched position, readily permitting further mechanical operations of building up the shoe, or repair, without interference with the stretcher. 90

It is to be understood that I do not limit myself to the preferred embodiment of my invention herein shown and described.

What is claimed is:

1. A shoe stretching last comprising separate vamp and heel portions, detachable means engageable therewith for forcing said portions apart and separate detachable means for holding said portions apart, while permitting the removal of the first named means from between said portions. 95

2. A shoemaker's last comprising separate vamp and heel portions, detachable means for forcing said portions apart longitudinally and separate adjustable, detachable means 105 for holding said portions apart while permitting the removal of the first named means from between said portions.

3. A shoe stretching device comprising separate vamp and heel portions, detachable means for forcing said portions apart and separate detachable means for holding said portions apart, said holding means being adapted to maintain the measurement of the distance of separation caused by said forcing 110 means and to return said portions to said distance. 115

4. A shoe stretching device comprising separate vamp and heel sections shaped to conform roughly to the corresponding portions of the shoe, power multiplying stretching means detachably connected to said vamp and heel sections, and clamping means for holding the vamp and heel sections in stretched position, permitting removal of the stretching means without displacement of the vamp or heel sections. 120 125

5. A shoe correction device comprising vamp and heel sections of skeleton form, means for separating the sections longitudi- 130

nally and means for holding the stretched sections against displacement while permitting the removal of the first named means from between said sections.

- 5 6. A shoe stretching last comprising vamp and heel sections, each provided with means to receive a stretching device and a clamping device, a shoe stretching device including relatively movable members, removably
10 connected to one of the receiving means of said vamp and heel sections, whereby the sections may be separated longitudinally to stretch the shoe to the desired shape, and a clamping device adapted to be connected in
15 the other of the receiving means of said vamp and heel sections, while said sections are in extended position thereby to hold said sections in extended position and permit the removal of the stretching device from said sec-
20 tions.
7. A shoe stretching device comprising vamp and heel sections each being provided with a stretching device receiving recess and clamp receiving recesses, a stretching device
25 including extendable sections adapted to be removably seated in said first named re-

cesses whereby said vamp and heel sections may be adjusted longitudinally under pressure to stretch the shoe to desired shape, and a clamping device removably seated in the 30 clamp receiving recesses of said sections adapted to hold the sections in stretched position while permitting the ready removal of the stretching device therefrom.

8. A shoe stretching device comprising 35 separate vamp and heel sections, a stretcher having extendable sections removably connected to said sections by means of pivotal connections, whereby said vamp and heel sections are connected for relative pivotal move- 40 ment permitting the sections to be accommodated to the shape of the shoe when in stretched position, and removable clamping means adapted to be engaged in portions of the vamp and heel sections to hold them in 45 adjusted position permitting the entire removal of the stretcher from between said sections.

In testimony whereof, I have signed my name to this specification.

ALBERT GODSHO.
